ELECTION RETURNS COUNTED.

Boston Type Foundry, No. 104 Milk Street, Boston.

UNITED STATES PATENT OFFICE.

JOHN K. ROGERS, OF BROOKLINE, MASSACHUSETTS.

DESIGN FOR PRINTING-TYPE.

SPECIFICATION forming part of Design No. 13,197, dated August 15, 1882.

Application filed July 13, 1882. Term of patent 3½ years.

To all whom it may concern:

Be it known that I, JOHN K. ROGERS, a citizen of the United States, residing at Brookline, in the county of Norfolk and State of Massachusetts, have invented and produced a new and original Design for a Font of Printing-Types, of which the following is a specification.

The types composing this font consist of an alphabet of capitals with figures, points, end piece, and center piece, also two spaces. The letters are of the Roman form with heavy lines and ceriphs, each letter and character be-

ing open and surrounded with a heavy ground and connecting with every other closely, so that when printed on white paper with black ink, as in the accompanying impression, taken from the types themselves, a white letter is produced with a black ground.

I claim—

The design for types, as described and shown.

JOHN K. ROGERS.

Witnesses:

D. W. ROGERS,
E. PAYSON FISHER.
